WORK CABINET

Everett A. Babcock, 204 W. Seaman Ave.,
Freeport, N.Y. 11520

Filed Dec. 30, 1965, Ser. No. 397

Term of patent 14 years

(Cl. D33—19)

The side of the cabinet not shown is a mirror image of the side shown while the back is plain and unornamented.

The design is characterized by a pair of drawer elements housed within the forwardly projecting upper front portion in combination with an open front section and a pair of sliding doors, all as shown.

I claim:

The ornamental design for a work cabinet, as shown and described.
